CLAIM

The ornamental design for a jewelry ornament, as shown and described.

DESCRIPTION

FIG. 1 is a perspective view of the jewelry ornament.

FIG. 2 is a front view of the jewelry ornament.

FIG. 3 is a back view of the jewelry ornament.

FIG. 4 is a right side view of the jewelry ornament.

FIG. 5 is a left side view of the jewelry ornament; and,

FIG. 6 is a bottom view of the jewelry ornament.

The broken lines shown on FIG. 3 of the drawings represent unclaimed portions of the design and form no part thereof.
